UNITED STATES PATENT OFFICE.

HENRY A. STEARNS, OF LINCOLN, ASSIGNOR OF TWO-THIRDS TO JOSEPH R. BROWN, OF PROVIDENCE, RHODE ISLAND, AND JOHN M. HALL, OF WALLINGFORD, CONNECTICUT.

AUTOMATIC FIRE-EXTINGUISHER.

SPECIFICATION forming part of Letters Patent No. 245,884, dated August 16, 1881.

Application filed February 5, 1881. (No model.)

To all whom it may concern:

Be it known that I, HENRY A. STEARNS, of Lincoln, in the county of Providence and State of Rhode Island, have invented a new and useful Improvement in Automatic Fire-Extinguishers; and I hereby declare that the following is a full, clear, and exact description of the same, reference being had to the accompanying drawings, forming part of this specification.

This invention has reference to an improvement in self-acting fire-extinguishers secured to a system of pipes distributed through a building, and consisting in the peculiar construction of the distributor and the means for closing the outlet, as will be more fully set forth hereinafter.

The object of this invention is to simplify the construction, facilitate the cleaning of the distributor, and insure the prompt action of the device.

Figure 1 is a view of my improved automatic fire-extinguisher. Fig. 2 is a sectional view of the same, showing a nipple the end of which is closed, with a ball secured in the nipple by means of solder fusible at a low temperature, and a perforated rose-sprinkler, the lower part of which is provided with a large hole, in which the ball rests when released.

In the drawings, *a* is a nipple, provided with the screw-thread *b*, by which it can be screwed onto a pipe, and the screw-thread *c* on its other surface, to receive the rose-sprinkler *d*. The end of the nipple *a* is provided with a seat to receive the ball *e*. The ball *e* and the seat on the nipple are trimmed, and the ball is secured to the nipple by a solder made of bismuth or similar material, so as to melt at a low temperature.

The device is used suspended below the system of pipes, with the opening pointing down-

ward, so that the ball *e* will drop from the seat in the nipple *a* and open the outlet by gravity as soon as the solder is melted.

An ordinary rose-sprinkler may be loosely 45 screwed over the nipple, as the joint need not be water-tight, and such a rose or other sprinkler may be removed from time to time to clean the same; but I prefer to use a sprinkler such as is shown in the drawings, in which all the 50 holes are on the upper half of the sprinkler, so as to spray against the ceiling, and the large hole *f*—nearly as large as the ball *e*—is placed at the lower part below the ball, so that the sprinkler can be cleaned without being removed, and 55 that the hole will be closed by the ball when released and the water be forced through the perforations. By this arrangement any of the old systems in which rose-sprinklers are used, and which are supplied with water from a system of pipes operated by means of valves, can be made automatic by making nipples of the proper size, soldering a ball into the end of the nipple, and interposing the nipple between the pipe-outlets and the rose-sprinkler. Each outlet will then open automatically when influenced by a fire sufficient to melt the solder, and the available water-supply will be concentrated 60 on the sprinklers near the fire, avoiding excessive damage by water and confining the damage by fire.

Having thus described my invention, I claim as new and desire to secure by Letters Patent—

The combination, with the nipple *a*, of the ball *e*, secured by solder, and the sprinkler *d*, 75 provided with the hole *f*, constructed substantially as and for the purpose described.

HENRY A. STEARNS.
